(57) **CLAIM**

The ornamental design for an anchor pad, as shown and described.

DESCRIPTION

FIG. 1 is an isometric view of the anchor pad of the present invention;

FIG. 2 is a top plan view of the anchor pad shown in FIG. 1;

FIG. 3 is a bottom plan view of the anchor pad shown in FIG. 1;

FIG. 4 is a rear elevational view of the anchor pad shown in FIG. 1;

FIG. 5 is a front elevational view of the anchor pad shown in FIG. 1;

FIG. 6 is a right side elevational view of the anchor pad shown in FIG. 1, the left side view being a mirror image of the illustrated view;

FIG. 7 is an isometric view of the anchor pad of the present invention;

FIG. 8 is a top plan view of the anchor pad shown in FIG. 7;

FIG. 9 is a bottom plan view of the anchor pad shown in FIG. 7;

FIG. 10 is a rear elevational view of the anchor shown in FIG. 7;

FIG. 11 is a front elevational view of the anchor pad shown in FIG. 7; and,

FIG. 12 is a right side elevational view of the anchor pad shown in FIG. 7, the left side view being a mirror image of the illustrated view.

Broken lines, where utilized, are for illustrative purposes only and are not intended to limit the claimed design to the features shown in broken lines.
